UNITED STATES PATENT OFFICE.

ELI B. HAYES, OF BIG RAPIDS, MICHIGAN.

PLANING-MACHINE.

SPECIFICATION forming part of Letters Patent No. 296,562, dated April 8, 1884.

Application filed December 10, 1883. (No model.)

To all whom it may concern:

Be it known that I, ELI B. HAYES, of Big Rapids, Mecosta county, in the State of Michigan, have invented new and useful Improvements in Blind-Slat Machines; and I do hereby declare that the following is a full and accurate description of the same.

The points of superiority of my machine may be stated in a general way: first, in the general design, securing strength, solidity, and compactness; second, in the method of work, whereby the edge of the slat is beaded before the sides are planed; third, in the overhanging upper bed, all of which will be particularly described hereinafter with reference to the accompanying drawings, wherein—

Figure 1 is a perspective view of my machine. Fig. 2 is a plan of the same. Fig. 3 is a side elevation of the same. Fig. 4 is a plan of the adjustable bed. Fig. 5 is a side elevation of the same. Fig. 5^a is a transverse section of the same. Fig. 6 is a plan of the adjustable bed. Figs. 7, 8, 9 represent the several stages through which the slat passes in being planed.

The bed A is cast in one piece, with laterally-projecting side pieces or ribs, *a*, to which the brackets B are bolted for the attachment and support of the spindles C for the edge-cutters D D. There are two feed-rolls, E E, mounted on horizontal shafts transverse to the machine, mounted in the ordinary housing, with regulating-screws *a'*, to adjust the rollers to materials of different thickness or to different pressures, as may be required. The two feed-rolls are geared together.

On the side of the machine opposite the feed-roll gears I place upon the shaft of the lower feed-roll a gear-wheel, F, of twelve inches diameter, or thereabout, and upon a stud, G, properly located below, I place a pinion, H, in mesh with said gear-wheel F, to drive it. A pulley, I, and idler J are placed upon the same stud, G, and are connected with said pinion, to transmit motion thereto.

The brackets B are provided with hand-screws L, whereby they may be moved out or in upon the ribs *a*, for the purpose of adjusting the edge-planers to slats of different widths.

The cutter-spindles C are provided with pulleys K.

The slat is fed against a stationary gage, *b*,

on one edge, and said gage is constructed to serve as a chip-breaker for the edge-planer on that side. At the other side I place a yielding circular chip-breaker, *d*, and attach the same to the casting in which the box for the spindle C is mounted.

The upper and lower boxes of the upper planing-cylinder, M, are yoked together strongly, and by means of the hand-wheels and screws *e* they can be raised and lowered and always kept in perfect line, thus giving the operator all conveniences for making slats of any desired thickness. The lower planing-cylinder, N, is placed near to the rear end of the frame, for reasons which will appear further on.

The overhanging bed P is a metallic frame or plate hinged to the bed-frame A by pivot-pins *g g* at one end of said frame P, and located on frame A between the planing-cylinders M and N. Its office is to hold and guide the slat while the planing-cylinder N is dressing its under side, and to that end it is made adjustable up or down, and also adjustable to fit the transverse configuration of the upper surface of the planed slat, so that slats of various widths, thicknesses, or form may be provided for. The frame P is therefore provided at its free end with a yoke-plate, *h*, which is suspended from the free end of the bed by four stud-bolts, *i*, having rubber washer-springs *k* and nuts *l*, whereby the distance between the yoke *h* and frame P may be adjusted, but yet left with a slight elasticity. There are also two adjusting-screws, Q, by means of which the frame P and the yoke-plate *h* may be regulated. The yoke-plate surrounds the planer-cylinder N, and one edge of the orifice through which the cutters revolve acts as a chip-breaker for said cutters.

The under surface of the frame P above the yoke *h* is also provided with a set of changeable bars, *q q*, the lower surfaces of which are made to conform to the planed side of the slat. For this purpose I unite the bars *q q q* transversely by means of a strip of spring metal, *r*, so that their relative positions transversely may be changed by the adjusting-screws *t*. The center bar *q* is bolted firmly to the frame P, and they may be removed and bars of other pattern substituted, if desired.

The main driving-shaft R of the machine is mounted in suitable boxes beneath and trans-

verse to the frame A. It is provided with a large leading-pulley, S, at one end in plane with the planer-pulleys T U. The main belt V, driven from the pulley W on the overhead shaft, passes down, in the direction of its motion, around the leading-pulley S, and thence backward under and around the lower planer-pulley, T, thence forward under and around the upper planer-pulley, U, and back to driving-pulley W, so that both planing-cylinders are driven directly by the same belt, and differences in adjustment of said cylinders under their ranges of adjustment will not change appreciably the traction of the belt. The shaft R is also provided with pulleys u u—one on each side of the frame—from which belts are led to the pulleys on the spindles C C, respectively, to drive the edge-planers D D. There is also a pulley, y, upon the shaft R, from which a belt is led to the pulley I, to drive the feed-rolls, as heretofore stated.

It is a well-known fact that edging-cutters for blind-slats wear down or nick in the center more rapidly than at the edges, because, the slats being planed first on the sides, the ends of the edging-cutter necessarily overrun a little and have less work than at the center. This is a great practical difficulty present in every machine heretofore, so far as I am aware, and entirely obviated by my improvement, which renders it possible to employ a regular beading-cutter, which planes the edge of the slat in the form shown in Fig. 7, and therefore encountering equal labor at all parts of its cutting-edge, and avoiding "nicking" entirely.

Having described my invention, I claim as new—

1. A blind-slat-planing machine provided with bead edging planers and concave top and bottom side planers, the edging-planers arranged to act in advance of the top and bottom planers, whereby the edging-planers do not become nicked by use, as set forth. 40

2. The bed-frame A, provided with brackets for the shafts of the top and bottom planing-cylinders, M N, the shaft R and leading-pulley S intermediate said planing-cylinders, and the driving-belt V, led over said pulley S and over the pulleys T U successively, as and for the purpose set forth. 45

3. The planing-cylinders M N, combined with the pivoted overhanging frame P, jointed to the frame A by pins g intermediate the planers, said frame P being provided with the yoke h and the adjustable bed-pieces q, substantially as and for the purpose set forth. 50

4. In a planing-machine fitted with planing-cutters arranged to plane the under side of the stuff as it passes the machine, and in combination with said under-side planer, an overhanging frame, P, pivoted to the main frame, and provided with a planing-bed to hold the stuff against the action of the cutters, said overhanging frame being capable of turning back on its pivots to expose said cutters and make 60 them easily accessible for adjustment or sharpening. 65

ELI B. HAYES.
